James Plachy INVENTOR

Arthur Clegg Jr.
WITNESS:

BY *Victor J. Evans*
ATTORNEY

UNITED STATES PATENT OFFICE

JAMES PLACHY, OF CLEVELAND, OHIO, ASSIGNOR TO PROOF MACHINE AND BRASS FOUNDRY COMPANY, OF CLEVELAND, OHIO, A CORPORATION OF OHIO

BATTERY CONNECTER

Application filed November 26, 1928. Serial No. 321,975.

The object of this invention is to provide a terminal connection for automobile batteries and the like, by use of which the operation of soldering the device to the wire forming part of the battery circuit is avoided, so that anyone can without previous experience apply or replace a connector within a very few minutes, after exposing one end of the conductor and applying the elements of the connector to the battery terminal and the wire in substantially one operation.

A further object is to provide a device comprising two clamping jaws forming together two socket portions, one of which engages the wire, and the other of which connects with the battery terminal.

A further object is to provide for securing the elements of the device and effecting both clamping operations simultaneously, by the use of a single securing device or bolt.

With the foregoing and other objects in view, the invention consists in the novel construction and arrangement of elements described, illustrated and claimed, it being understood that modifications may be made within the scope of the claim without departing from the spirit of the invention.

In the drawings forming part of this application:

30 Figure 1 is a view showing the device in top plan.

Figure 2 is a view in elevation.

Fig. 3 is a view in longitudinal section.

35 Figure 4 is an elevation of one of the clamping elements or jaws.

The conductor or wire to be connected is designated 10 and one end thereof has been scraped or exposed as shown at 11 and is to be connected with a battery terminal 12.

40 A plurality of clamping jaws or clamping elements 13 and 14 are formed to correspond with each other in general contour, but have concaved portions oppositely located when assembled, so that socket portions are formed

45 at opposite ends of the complete device, the socket portions being perpendicular with reference to each other.

The jaws 13 and 14 have concaved portions such as 13' and 14', the walls of which 50 are so formed as shown in Figure 4 that a

tapered socket is produced for engaging the battery terminal 12. The tapered portion is designated 15 in Figure 4.

The socket portions at the opposite end of the clamping device or connector are formed by the concave portions shown in Figures 3 and 5, the walls of these portions being roughened or corrugated as shown at 16, so that positive engagement with the bare wire 11 may be effected.

Intermediate of the socket portion for the terminal and socket portion for the wire, flat surfaces are provided at 17, and this portion may be regarded as constituting a shank portion of the clamping element or jaw, apertures being produced as shown at 18, and the apertures being in alignment under the conditions illustrated in Figure 3, so that the connecting device such as a bolt 20 may pass thru each jaw and may be secured by means of a nut 20, thereby providing positive engagement of the elements to be clamped, and in one operation.

If necessary or desirable, spacing means, in the nature of a shim, may be used in either 75 socket, in order that the required engagement may be produced regardless of the exact size of the elements to be connected.

Having described the invention what is claimed is:

80 A battery connecter comprising a pair of parallel arranged members having aligned openings intermediate the ends thereof, said members having recesses in the opposing faces thereof to form a socket to receive an electric conductor, said recesses having the walls thereof serrated to grip the conductor and extending through a pair of ends of said members, the other pair of ends of said members curved and having concaved opposing faces to engage a battery terminal, and a fastening element extending through the openings to cause said members to grip the terminal and the conductor.

85 In testimony whereof I affix my signature. 95

JAMES PLACHY.
